United States Patent Office

Des. 191,950
Patented Dec. 19, 1961

191,950

LACE

William E. Arfa, New York, N.Y., assignor to Arfa Mills
Inc., New York, N.Y., a corporation of New York

Filed Mar. 7, 1961, Ser. No. 64,172

Term of patent 14 years

(Cl. D47—6)

FIG. 1.

FIG. 2.

FIG. 1 is a front elevational view of a lace embodying my new design; and

FIG. 2 is an enlarged edge view thereof.

I claim:

The ornamental design for a lace, substantially as shown.
